UNITED STATES PATENT OFFICE.

HERBERT LONG, OF WALTHAMSTOW, LONDON, ENGLAND, ASSIGNOR TO TAYLOR INSTRUMENT COMPANIES, OF ROCHESTER, NEW YORK, A CORPORATION OF NEW YORK.

DESIGN FOR A BAROMETER.

Application filed September 27, 1926. Serial No. 19,180. Term of patent 14 years.

To all whom it may concern:

Be it known that I, HERBERT LONG, a subject of the King of Great Britain, residing at Macdonald Road, Walthamstow, London, E. 17, have invented a new, original, and ornamental Design for Barometers, of which the following is a specification, reference being had to the accompanying drawing, wherein—

Fig. 1 is a front view of the barometer, showing my new design, and

Fig. 2 is a side view thereof.

I claim:

The ornamental design for a barometer, as shown.

HERBERT LONG.
